UNITED STATES PATENT OFFICE.

WILLIAM ERASTUS WILLIAMS, OF CHICAGO, ILLINOIS.

STEEL BOX-CAR.

1,237,434.

Specification of Letters Patent. Patented Aug. 21, 1917.

Application filed November 21, 1914. Serial No. 873,295.

To all whom it may concern:

Be it known that I, WILLIAM ERASTUS WILLIAMS, a citizen of the United States, residing at Chicago, in the county of Cook 5 and State of Illinois, have invented a new and useful Improvement in Steel Box-Cars, of which the following is a specification.

The object of my invention is to produce a very strong, cheaply constructed and light 10 weight box car and one that will be neat in appearance and have various special merits as will be noticed from the specification and drawings, and as set forth in the claims. The invention consists in the construction 15 and combination of parts as set forth in the claims.

Reference will be had to the accompanying drawings in which Figure 1 is a side elevation of a railway box car, a part of 20 which is cut away for lack of space for illustration. The trucks of the car are not shown nor are some of the parts that relate to the underframing.

Fig. 2 shows a plan sectional view through 25 the walls of one corner of the car.

Fig. 3 shows an end elevation of a corner of the car looking from the outside of the car.

Fig. 4 is an end sectional elevation of the 30 corner of the car looking from the inside of the car toward the end of the car, the end wooden sheathing being omitted.

Fig. 5 is an elevation of the door section of the car with parts broken away.

Fig. 6 is a sectional elevation through the 35 door looking in line with the length of the car as indicated by the direction of the arrow 6 of Fig. 7.

Fig. 7 is a plan section through the door 40 post and door with parts broken away for lack of room.

Fig. 8 is an enlarged view showing the structure appearing in the upper part of Fig. 6.

Fig. 9 is a perspective detail of the top end 45 of the spark strip which is fastened to the door.

Fig. 10 is a plan detail of the top of the car at one of the corners of the roof.

Fig. 11 is a plan sectional detail similar 50 to that of Fig. 10 but taken lower down.

Fig. 12 is a plan sectional detail showing the parts at the corner of the car where the end and side sills join, on lines 12-12 of 55 Fig. 4.

Fig. 13 is a sectional view looking endwise

of the car showing the side sill and showing the connection of one of the intermediate cross bearers of the underframe with the side sills. 60

Fig. 14 is an elevation of the junction of the left hand door post with the side plate at the eaves of the car.

Fig. 15 is a vertical sectional elevation similar to Fig. 14 but transversely thereof. 65

Fig. 16 is an end elevation of one of the roof corners of the car looking from the end of the car.

Fig. 17 is a perspective view of the side plate pressing which forms part of the side 70 plate where it joins the roof at the end of the car.

Fig. 18 is a perspective view of the end of the side plate of the car.

Fig. 19 is a perspective view of the end of 75 the sheathing at the top corner of the car.

Fig. 20 is a perspective view of one end or corner of one of the sheets which compose the end of the car.

Fig. 21 is a perspective view of the end 80 of the end plate of the car.

Fig. 22 is a cross sectional elevation showing the inside sheathing for the end of the car.

Fig. 23 is a plan view of one of the cross 85 bearers or needle beam connections with the side sill.

Fig. 24 is a plan view of the body bolster connection with the side sill.

Fig. 25 is a plan view of the connection 90 between the end and side sills and the diagonal strut at this point.

Fig. 26 is a plan section through the door.

Fig. 27 shows the outer face of a portion 95 of the outside sill.

Fig. 28 is a section on the line 28-28, of Fig. 27.

With my invention, I prefer to form the side sheathing of the roof of the car, in such a manner that the sheathing and the roof 100 themselves will furnish all of the strength and stiffness required without the framework which has hitherto generally been used, and by doing this, I am enabled to make a lighter weight car for the same service and also to provide a little more room within the clearance ordinarily given for box cars, and further, I am enabled thereby to have wall structures for a box car that will be stronger in the weakest areas against 110 injuries at small points of contact, than is the case where framing is used covered with

a sheathing which depends upon the framing to furnish the stiffness, as in the latter case, the frame posts are comparatively far apart and unsupported sheathing must span the intervening space.

My invention makes the outside of the car nearly smooth and of such a nature that it will shed the water more completely and furnish no horizontal or inclined shoulders to catch and hold moisture and induce corrosion as is the case with some other designs of steel box car construction.

The corrosion of the metal of which steel cars are made is the greatest objection to the use of steel in the manufacture of cars, and corrosion is greatly delayed and reduced by avoiding external ledges and crevices from which water will not quickly flow. Where the sheathing is thin metal, such ledges and joints may cause the whole structure to be seriously weakened by corrosion while the body of the thin metal is substantially intact; and it is thought that the construction here set forth minimizes this evil.

25 It is desirable with many classes of goods which are shipped in box cars, to have the car insulated from too high temperatures and also it is desirable that the inside surface of the car should furnish a wooden surface for contact with the loading instead of a metal surface, and my construction permits the use of a wooden insulation on the inside of the car together with an air space and yet consumes less space for the wall thickness of the sides of the car than is ordinarily used with a car having the same rigid stiffness and general strength for the body of the car.

The manner of forming the steel ends of my car permits a lighter weight of metal for the same strength than any other construction heretofore used so far as I am aware, and at the same time provides a form which permits of wooden insulation at a less expense than the steel ends heretofore commercially used, and also this construction is such that in sheathing the end there is less trouble in filling all the spaces and escaping the chance of leaving voids beneath the sheathing which might gather dirt and provide space for the permanent residence of insects or vermin which might at times injure the load of the car.

55 The roof section of my car, while it furnishes the necessary stiffness and strength for the top of the car without other framing, is also of such a form as to take up by its own elasticity, any deflections produced by the yielding of the whole car body when 60 it receives severe shocks that all cars are required to meet at times. Many forms of metal roofs are seriously injured by the distortions produced in the car body and by severe shocks.

65 In a steel sheathed car it is desirable to

have the side sills very stiff laterally and yet use as little metal as can safely be used, and if the sheathing is so formed that it can be relied upon to furnish sufficient vertical stiffness, then the metal on the side sill may 70 be used chiefly for lateral strength and my invention provides, this, and hence I get a stronger construction for the same metal along the side sill of the car than has heretofore been obtained by steel box car constructions. 75

In the drawings, 1 indicates the sheathing for the sides of the car (see Figs. 1 and 2). This sheathing is made up of sheets which extend vertically and they are stiffened at 80 suitable intervals by ribs or flanges 2 which are formed from the body of the sheet by suitable bending operations. The sheets are joined together as indicated by 3, Fig. 2 wherein a rib or flange of one sheet is embraced by the rib or flange member of the edge of the adjacent sheet, and thus when the sheets of the sheathing are in place on the car, the outside appearance does not disclose the line of the joints on the edges of the 85 several sheets. At the ends of the car the edge of the side sheathing bends around the end at the corner as indicated by 4.

The side sill of the car is made of two pieces, riveted together forming a section 95 which might be termed a channel T section. This is shown most clearly by Figs. 3, 4 and 6. The lower piece of this side sill section is indicated by 5 and the upper piece by 6 and the rivets which join the pieces are indicated by 7. These pieces 5 and 6 are first punched in the flat with series of slots spaced along their edges at the intervals where occur the ribs 2 and 3 of the side sheathing or siding of the car. When after 105 these notches or slots are made in the flat bars 5 and 6, the bars are bent to the form shown providing the flanges 8 of bar 5 and 9 of bar 6 to which there is riveted by the rivets 10 and 11, the siding 1. The flanges 110 2 and 3 of the siding passing through the slots in the pieces abutting against the wall 12 of the piece 5. 13 indicates the floor of the car made of planks extending crosswise of the car and these planks are bolted to the 115 side sill members by the bolts 14 at suitable intervals in the length of the car on the inside of the siding.

Wooden blocks or posts 15 are fastened by means of the bolts 16 to the flanges 2 and 120 3 of the siding. To these posts 15 there is fastened by the nails 17, the inside wooden sheathing 18 of the car. In order that the post 15 may be held strongly against the outer wall of the siding, the post is formed 125 with a beveled edge 19 (see Fig. 2) which induces the bearing of the post 15 against the siding when the bolt 16 is tightly drawn. The siding 18 does not extend clear down to the floor, but there is a gap between the 130

bottom edge and the floor sufficiently wide to permit of the cleaning out of the spaces between the ribs or flanges 2 of the siding. The bottom edge of the inside wooden sheathing is indicated by 20 Fig. 4.

6 The end of the flooring planks stop at the inside edges of the flanges 2 and 3 and between these flanges there are filler blocks of wood 21 which are cut out at 22 to accommodate for the rivet heads 10. Then after the flooring and blocks 21 are in place, a nailing strip 23 is run along and nailed to the floor and to the blocks 21, thus assisting in holding the blocks 21 in place.

10 15 However, blocks 21 are inserted before the floor is laid, and if this is done the rivet heads of the rivets 10 will then hold the blocks 21 in place. Pieces of tar paper 23 are placed in contact with the metal between 20 the blocks 21 and floor 13 to insure a tight fitting joint there and to protect the metal surface from corrosion.

25 The car body bolster and cross bearers or needle beams as they are sometimes called, which are part of the underframing, are indicated by 24 in Fig. 4 and they are secured to the vertical web 12 of the piece 5 and to the horizontal webs or flanges of both pieces 5 and 6 as is indicated by 26 in Fig. 30 4. See also Figs. 23, 24 and 25.

35 The siding 1 (see Fig. 4) covers over the outside of the pieces 5 and 6 which form the side sill and thus make, as it were, a box girder of the side sill at all places save at the door opening or between the door posts. Between these posts, I rivet on a plate 27, (see Figs. 6 and 7) and thus this plate carries the box girder section the full length of the car. The top edge 28 of plate 27 is turned 40 over to furnish a flush edge to engage the edge of the sliding door along the line of its clearance with the side of the car and at the same time it extends beyond the heads of the rivets which fasten plate 27 to the side 45 sill members.

50 The siding 1 extends up and is fastened by the rivets 29 to the lower flange 30 of a Z bar 31 which forms the side plate or eaves of the car. The Z bar 31 is reinforced by a pressed strip 32 which is riveted to the Z bar by the rivets 33 and thus this piece becomes a part of the side plate itself and furnishes additional strength to it. The flange 34 of 32 (see Figs. 4 and 17) is 55 formed to fit the corrugated sheets 35 which form the roof.

50 The flange 36 of the Z bar 31 is cut out at the points 37 to clear the gutters of the corrugated roof sheets.

60 The roof sheets are fastened to the member 32 by clips 38, the vertical flanges of which are riveted to the side plate by means of the rivets 39 which pass through the clips themselves through the member 32 65 and the flange 36 of the Z bar. Thus, when

the roof is secured to the car, the member 32 is secured to the Z bar flange by a double row of rivets. Rivets 40 secure the plates 38 to the roof sheet at the top or summits of the corrugations.

70 The left door post is made of a sheet metal member 41, (see Fig. 7) and it extends down on the outside of the sheathing and is fastened to the side sill by rivets 42 (see Fig. 5). This post has the projection 75 43 which acts as the door stop and it has a wing 44 bent around into the door aperture and with an overlapping flange 45. A wooden post 46 is placed in the embrace of the flange 45, and is bolted at suitable intervals as indicated by the bolts 47. The post 41 is mutilated and bent at the bottom in a manner to provide a flange 48 (see dotted line in Fig. 7) which extends horizontally underneath the floor and is riveted by 80 85 rivets 49 to the side sill.

85 The post 41 is cut away at the top as indicated by 50, to fit under the flange 30 of the Z bar 31 of the side plate, but the sections 44 and 45 (see Figs. 14 and 15) extend up to the inside of the horizontal web 90 of the Z bar 31. A gusset plate 51 shown in dotted lines in Figs. 8, 14 and 15, connects the main flanges of post 41 to the A bar. These parts are secured together by rivets 52 95 and 53. An angle piece 54 fastened by rivets 55 to the flange 44 of the post, connects this flange to the web of the Z bar 31 by rivets 56, thus the post is securely fastened to the side plate.

100 The door rail or track for the door is indicated by 57 and is a Z bar riveted to the flange 30 of the side plate. The post projection 43 is bent inward at 58 Fig. 15, to bring it underneath the door rail 57 and thus shut off the rain from the cavity within the projection.

105 The right hand door post is indicated by 59 and it is also provided with a flange 60 in the door opening and an embracing 110 flange 61 which embraces a wooden post 62 secured in place by the bolts 63 and 64, (see Fig. 7). The lower end of this post 59 is fastened by rivets 65 to the side sill (see Fig. 5) and above the side sill a flange 66 115 of the part is bent outward to form a spark strip (see Fig. 7) and at the top where the flange 66 joins the flange 30 of Z bar 31 this spark strip section is cut loose for a short distance right on the line of the edge 120 of the flange 30 of the Z bar and the body section of the top end of the post is then bent inward to extend on the inside of the flange 30 of Z bar and rivets 67 fasten the top of the post to the Z bar. Angle plates 125 68 shown in dotted lines in Fig. 5 fasten the flange 60 to the web of the Z bar side plate in the same manner as the angle plate 54 does to the left hand post. The bottom of post 59 is mutilated and bent similarly to 130

the post 41 producing the flange 69 fastened by the rivet 70 to the side sills, (see Fig. 7). Thus the door posts are secured to both the side sills and the side plates.

5 The roof sheets 35 are made of corrugated sheets corrugated relatively very deep and extend in an arc from side plate to side plate all fastened as has been indicated, so securely to the side plates that 10 16 the roof sheet itself becomes the entire roof structure of the car. The ends of the roof sheets where they pass down onto the member 32 are flanged over as is indicated by 71, to prevent snow blowing underneath 15 the ends of the sheets.

A running board 72 is fastened to the roof sheet in any suitable manner, but I prefer to fasten it by means of the saddle blocks 73 bolted to the summits of the corrugations of the roof sheet at suitable intervals as required, (see Fig. 1).

The end of the car is made of a corrugated sheet 74 made in several pieces when desired and the corrugations extend cross-

20 25 wise of the car (see Figs. 3, 20 and 22).

These corrugations are made with substantially flat horizontal sections and flat vertical sections thus becoming almost a series of letter S's having square block sections as is indicated by 75 for the horizontal sections and 76 for the vertical sections. The purpose of this form of the main body of the corrugated end is to get as much metal on the front and back surface of the sheet as is

25 30 possible thus forming the equivalent of a series of box girders which form has less metal in the neutral axis to resist an end thrust of material in the car, than is the case when the ordinary form of curved corrugation is used.

This method of corrugating the end sheets for the ends, obtains a greater section modulus of resistance to resist bulging with a light sheet than can be obtained with the curved corrugations with

35 a much heavier sheet. A sheet of metal $\frac{1}{8}$ " thick corrugated as I have designed, will resist a greater end thrust of the car load than can be sustained by a $\frac{3}{16}$ " sheet having the old corrugations.

40 At the ends of the end sheets, I press down alternate corrugations as indicated by 77, Fig. 20, thus making the vertical sections 76 all in one plane where the ends of the sheets join the corner post and in doing this, the horizontal portions 75 are doubled on themselves making the flange 78 approximately half the width of the portion 75, (see Figs. 11 and 20).

I prefer to make the corner post of the car out of angle sections as is indicated by 45 50 79. One leg 80 of this angle embraces the siding and leg 81 embraces the end. A flange 4 of the siding 1 is curved around fitting the inside faces of the lines of the angle post 79 and for the greater part laps

55 60 65 over the ends of the end sheet, thus by means of the flange 4 the thrust of the end is carried to the siding independently of the rivets which may fasten the siding to the corner post.

On the inside of the angle corner post, 70 there is bolted a wooden post or block 83 secured in place by the bolts 84. This block 83 is notched out to receive the ends of the boards 85 of the wooden sheathing 18 and it is also notched out at intervals to embrace 75 the flanges 78 of the end sheets.

The angle post 79 is fastened to the flange 30 of the Z bar by means of the gusset plate 86 (see Figs. 3, 4 and 10 and 16), the flange 80 of the post 79 being cut away at 80 the point 87, Figs. 4 and 16, to join the flange 30 of the Z bar. A piece of tar paper or other suitable material 88 is placed in this joint to keep out the water and make a tight joint and an angle plate 89 shown in dotted 85 lines in Figs. 3 and 16 and in full lines in Fig. 4, secures the flange 81 of the corner post to the web of the side plate by means of rivets 90 and 91.

The corrugated end sheet may be made to 90 extend up into the roof sheet and become itself, the end plate of the car box, but I prefer to make the plate of a separate sheet the end of which is shown in Fig. 21 and is indicated by 92, for the vertical web portion 95 and 93 for the curved portion on to which the end corrugation 94 of the roof sheet fits as is indicated by Figs. 3, 4 16 and 22. This end plate is notched out at 95 to fit the side plate member 32 where it is notched out at 96 (see Figs. 17 and 21). A junction angle block 97 shown in full lines in Fig. 4 and in dotted lines in Fig. 16, join the vertical flanges 36 of the Z bar side plate to the end plate 92 by means of rivets 98 and 99. Thus 105 a very strong corner is produced.

The flange 4 of the siding where it turns around the end is notched out at 100 (see Fig. 19) to clear the corner 101 of the end plate, Fig. 21.

When the ends of the car are required to be sheathed with wood, every other corrugation is filled with a rectangular block as is indicated by 102 (see Figs. 3 and 22) and these blocks are fastened in place by some 115 oval strips running vertically on the inside as is indicated by 103 and they are fastened to the corrugated sheets by the rivets 104. Over the blocks 102 there extends the wooden sheathing running vertically as is 120 indicated by 105 and this is notched out to cover the strips 103 and is nailed to the blocks 102. Short blocks 106 are fitted into the spaces 107 at the ends of the end sheet at every alternate corrugation, thus filling 125 completely or nearly so, the entire space beneath the end sheathing 105 (see Figs. 3, 11 and 22).

In the event that the wooden sheathing is not used for the end, my flatly corrugated 130

end sheet is more desirable than the round faced corrugated sheet might be as regards injury to loading of furniture and other articles which might be jolted heavily in contact with the end.

- 5 The door of the car is made substantially in the same way as the siding, that is, it is provided with a sheathing stiffened by ribs or flanges substantially in the same manner 10 as the siding is stiffened (see Figs 5, 6 and 26) wherein 108 indicates the door sheet, and 109 the ribs. These ribs run vertically of the door. This door sheet may be made in one or more pieces having the joint edges 15 made substantially as is indicated by 3 for the siding, or may be made with an interlocking strip as is indicated by 110 of Fig. 26.

The door sheet or sheets have a Z bar 20 frame having vertical member 111 and the horizontal members 112. This frame is connected at the corners by Z bar angle blocks 113 and the door sheets are clamped on the inside of this frame by means of the angles 25 114 (see Fig. 7) on the inside or vertical members and by an angle 115 crossing at the top (see Figs. 6 and 7) and at the bottom by a Z bar section 116. Running across the door in the middle section there is a Z 30 bar cross piece 117. The cross piece angle 115 and the cross piece A bars 116 and 117 are notched out the depth of the flange 109 of the door plate so as to have one flange of the Z bar bear against the plate surface of 35 the door sheet. Filler blocks 118 and 119 made of wood are fitted in to be embraced by the upward projecting flanges of the Z bars 116 and 117. The purpose of this wooden filling is to furnish surface to receive 40 the impact of articles that may be improperly loaded and also to aid in the stiffening of the door.

The several parts which compose the door are riveted bolted or spot welded together 45 as desired and are shown in the drawings as being riveted.

The door is supported by the hangers 120 having rollers which run on the door rail 57 which is riveted to the side plate. The 50 bottom of the door is held within brackets 121 and 122 and by additional brackets on the body of the car which are not shown.

Brackets 121 and 122 are bolted as is indicated by the bolts 123 Fig. 6 to the side sill 55 of the car. These bolts are covered up on the inside by the flooring and when the door is closed the door itself covers the outside, thus the brackets can not be removed when the door is closed. Bolts 124 secure the bottom flange of the brackets and they are exposed and may be taken off by robbers who take the trouble to do so, but even when they are removed, the brackets themselves are still held by the bolts 123 which sustain practically all of the load and the bracket

bolts 124 do not invite the removal of the brackets. Bracket 122 is provided with an extension or lip 125 which continues to embrace the door edge when the door is open to its full width. This is desirable since a 70 bracket may not be securely fastened at the edge of the door when the door is open owing to the location there at this point of the right hand door post.

Extending along the right edge of the 75 door there is a spark strip 126 (see Fig. 7) which has a flange 127 that interlocks with the flange 66 of the right hand door post 59 thus closing the space against flying sparks which come from the locomotive. 80 This spark strip 126 is fastened to the side of the door by rivets or by any suitable means.

At the junction of the end and the side sill (see Fig. 25) I provide a casting 128 85 of any suitable material, but preferably of malleable iron or cast steel. This casting has a flange 129 that is secured to the wall 12 of the side sill and the flange 130 which is secured to the end sill 131. A diagonal 90 brace made of channel iron of any suitable form as is indicated by 132 is connected to the casting 128. A lip or flange 133 of casting 128 abuts against the end of the diagonal brace or strut 132 and assists in 95 taking up any shocks or push which is produced when the cars are switched by means of a pushing beam applied to the corner of the car as is sometimes done in switching cars in inconvenient places; the several 100 parts are here shown as riveted together at the corner.

At the bottom edge of the end sheet 74, I rivet an angle 134 (see Figs. 3 and 22) which angle has its lower leg covering the 105 end sill 131 and is riveted thereto.

I may, when desired, reverse the direction of this angle as is indicated by the dotted lines 135 in Fig. 3. By placing a heavy angle at the bottom of my end sheet, I secure a heavy piece of metal to encounter any severe strains that may come about from heavy iron bars in the bottom of the car or by damage that might be inflicted upon the end of the car by breaking of the coupler 110 connections; thus I am not compelled to carry a heavy sheet up the whole end where it is not needed, but I obtain safety by the insertion of the heavy angle 134 as indicated. 115

Where the body bolsters and the cross bearers or needle beams of the underframe, join the side sills, I reinforce the side sills a short distance by angles indicated by 136 (see Figs. 4, 6, 13, 23 and 24) wherein 137 125 and 138 indicate the rivets which secure the parts together. The cross bearers or needle beams are indicated by 139 and the body bolsters by 140, and both have built up members along their upper margins and 130

where they join the side sills there are angles or flange members having horizontal flanges as is indicated by 141 and these flanges are cut away where the junction of 5 the side sill is made and then on the top there is riveted a cover plate 142. The numeral 142 indicates the cover plate for both the needle beams and the body bolsters. The vertical flanges 143 of the cross bearers or needle beams and the corresponding flanges 144 of the body bolster are reinforced by angle plates 145 shown in dotted lines in Figs. 23 and 24, the numeral 145 being used in both figures. Rivets 146 se- 15 cure these angles to the several members.

By using the short reinforcing angles 136 where the cross bearers and body bolsters join, the side sills, I may use on an average a much lighter weight side sill and yet se- 20 cure a more rigid construction of the car than is otherwise possible and further this reinforcement at these plates guards against the weakening that might be produced by corrosion since corrosion is more likely to 25 take place at junction points of the members than along the smooth section of the side sill.

Across the door opening, I fasten on the angle plate 147, Fig. 8, which furnishes a 30 shoulder against which the edge of the door may engage in the event of a severe extraneous pressure coming upon it to force the door inward into the car beyond the strength of the door hangers to resist.

35 What I claim is:

1. In a steel box car, the combination with a roof and side plates supporting the roof, of side plate supporting side walls each having as its body and main support of said side 40 plates metal sheathing sheets bent to form numerous parallel closed folds whereby the outer faces of the folded sheets are practically plane and continuous and the inner faces provided with vertical ribs of doubled 45 metal to perform the offices of the common sheathing-covered, roof-supporting frame, while presenting finished external appearance and affording ready attachment for light car lining.

50 2. A box car having an underframe, floor structure, roof structure, end structure, and side walls, the roof structure composed of curved corrugated sheets and the side walls composed of flat sheets stiffened by ribs or 55 flanges on one side extending vertically and furnishing the stiffening framework for the side wall of the car and the end sheets stiffened by horizontal corrugations; with side plates suitably shaped and forming the 60 connection between the roof sheets and side walls.

65 3. A metal box car having a roof structure composed solely of transversely arched corrugated metal and a side structure composed of flat sheets stiffened by vertically

extending ribs, an end structure composed of horizontally corrugated sheets; with side plates joined on one of its margins to the roof sheet and another margin to the side sheet and the end sheet suitably joined to 70 the side sheets.

4. A box car having side sills which latter have horizontal extending flanges adapted to support and be engaged by the ends of the floor members and having vertically ar- 75 ranged flanges adapted to be fastened to the sheathing said vertical flanges slotted to permit the entrance of stiffening ribs or flanges for the sheathing.

5. A steel box car having a side wall com- 80 posed of a sheathing stiffened by ribs or flanges extending on the inside of the car; with side sills slotted on the side to receive flanges of the sheathing and having vertical webs adapted to support an underframe 85 member, horizontal members adapted to be engaged and supported by the underframe member and to support the ends of the floor- ing.

6. A box car having a sheathing stiffened 90 by a series of vertically arranged flanges extending on the inside of the car with a side sill having a vertical web extending along the summits of the flanges of the sheathing and horizontal flanges extending 95 from the vertical web in a manner to permit the web to support the floor and in turn to be supported by the cross bearers and the bolsters of the car.

7. A box car having a sheathing stiffened 100 by vertically arranged ribs, the said sheath- ing extending down across the vertical face of the side sills; with side sills notched out to permit the entrance of the ribs of the sheathing and provided with flanges adapted 105 to be secured to the flat surfaces of the sheathing.

8. A steel box car having a steel sheath- 110 ing, a box girder side sill, the said sheath- ing forming one side of the box girder and a flange extending from the box girder toward the inside of the car for the purpose of assisting in the support of the floor and for the fastening of the underframe to the side sills.

115 9. A box car having a sheathing stiffened by vertically arranged flanges on the inside of the car, side sills in the form of a box girder, one side of the said box girder produced by the flat surface of the sheathing, the said girder slotted to permit the entrance of the stiffening flanges of the said sheathing, flanges extending horizontally inwardly from the side sill to assist in sup- 120 porting the floor and for attachment to the underframe.

125 10. In a box car, the combination with a side sill having a longitudinal U-shaped recess along its outer face, upper and lower vertical flanges at that face, and a hori- 130

- zontal flange projecting from the upper part of the opposite or inner face, of metal sheathing rigidly secured to said vertical flanges and covering said recess. 5
11. A box car having a sheathing stiffened by vertically arranged flanges, side sills to which the said sheathing is fastened on the flat surface of the sheathing, the said side sills relatively weak in vertical arrangement, relying upon the sheathing for the chief stiffness in this direction and said side sills having relatively stiff horizontal flanges with angular stiffening members for a short distance along the side sills where the body bolsters join the side sills. 10
12. A box car having a metal sheathing stiffened by vertically arranged flanges, with a door post joining the sheathing and secured at the bottom to the side sill and at the top to the side plate, and said door post composed of sheet metal formed with a projection adapted to act as a door stop, a horizontal face adapted to fit the flat surface of the sheathing where it joins the side sill and an inwardly projecting flange adapted to form the edges of the post in the door entrance. 15
13. A sheet metal door post formed with a flange parallel with the line of sheathing and a projection extending from this flange at right angles to the sheathing forming the door stop and having a secondary vertical flange in line with the first mentioned flange and having a flange extending in the door way and constituting the sides of the door post at the entrance of the car. 20
14. A one piece sheet metal door post having next the door opening a straight vertical member U-shaped in cross section, the outer wall of the said member being bent outward to form a second outwardly closed member of like cross section to serve as a door stop. 25
15. A door post having surfaces parallel with the side walls of the car and connected to the side plate by means of a gusset plate and having a surface extending in the car in the door way forming the edge of the post and connected by a reinforcing angle to the side plate and said angle forming the corner made by the door post and the side plate. 30
16. A sheet metal door post of substantially channel shape, the web of the channel forming a wall of the post in the door opening and one leg of the channel on the inside extending parallel with the walls of the car and the other outer leg extending parallel with the outside face of the sheathing, this latter face connected at the top to the side plate and at the bottom to the side sill. 35
17. A sheet metal door post, for the right hand side of a door opening, bent to form a vertical channel, the web of said channel forming the edge of the post extending in
- the door opening, one plate of the channel forming the inside edge of the post parallel with the walls of the car, and the other leg of the channel substantially parallel with the sheathing on the outside of the car, this latter leg of the channel fastened at the top to the side plate and at the bottom to the side sill and the edge of this leg between the said side plate and side sill projecting outward from the sheathing of the car forming a spark strip. 40
18. A box car having a Z bar side plate, said Z bar arranged with its main web horizontal and its upwardly extending flange or leg on the side toward the inside of the car, and its downwardly projecting flange or leg on the outside forming the eaves of the car; with a metallic sheathing secured to the inside of the outside downwardly projecting flange or leg of the Z bar. 45
19. A box car having a Z, bar side plate and the said side plate lying with its web horizontal forming a part of the roof shedding surface, and with the outside flange or leg of the Z bar extending vertically forming, the eaves of the car with a sheathing secured on the inside of the eaves leg. 50
20. A box car having a Z bar section forming the side plate, the webs of said Z bar disposed horizontally and forming part of the shedding surface of the roof and the outside leg of the Z bar extending downward and forming the eaves of the roof, a sheathing united to the eaves leg of the Z bar; with a door rail secured to the vertical face of the eaves leg of the Z bar. 55
21. A box car having a Z bar side plate made with its web horizontal and forming a part of the shedding surface of the roof and having the inside leg extending upward and joining the roof, the outside leg of the Z bar extending downward forming the eaves of the roof; with a Z bar door rail secured to the eaves leg of the Z bar of the side plate. 60
22. A box car having a Z bar side plate and angle corner post, the web of the said Z bar disposed horizontally forming part of the shedding surfaces of the roof and covering the top end of the corner post, an angle block connecting one flange of the angle post with the web of the Z bar and a gusset plate connecting the other leg of the angle with one of the legs of the Z bar. 65
23. A box car having a Z bar side plate, an angular corner post and a steel end plate, the said end plate united to one flange of the angle post and also united to the Z bar and the corner angle post connected by an angle plate to the Z bar side plate, a roof structure connected to the end plate and to the Z bar side plate. 70
24. A steel end for a car composed of a corrugated sheet or sheets with corrugations extending crosswise of the car and so shaped

that the valleys of the corrugations will be substantially rectangular in cross section; with wooden blocks inserted in every other valley on the inside of the car.

5 25. A car having a steel end composed of a sheet or sheets of corrugated metal the corrugations extending crosswise of the car and so shaped that the valleys of the corrugations are substantially rectangular in cross 10 section and have their side faces or webs substantially perpendicular to the general plane of the car end; with wooden blocks inserted in every other corrugation on the inside of the car and secured therein and a 15 wooden sheathing covering over the wooden blocks and over the metallic faces of the summits of the alternate corrugations.

26. A car having a steel end composed of corrugations extending across the car and 20 the valleys of the corrugations on the inside of the car filled with wooden strips; with metal bands on the inside of the car extending across the corrugations and inclosing the wooden strips in the valleys of the corrugations and fastened to the summits of the adjacent 25 corrugations.

27. A car having a steel end stiffened by corrugations running across the car, a steel sheathing on the sides of the car, an angle 30 corner post embracing on the outside, the end of the sheets, and the end of the side sheathing being secured thereto; with a Z bar side plate extending across the top of

the angle corner post and having a flange extending over the top of the side sheathing 35 and the several parts being secured firmly together.

28. A car having a steel end plate, a Z bar side plate, an angle corner post and a steel sheathing, and a roof structure, the sheathing being connected to one leg of the Z bar side plate and the roof structure connected to the other leg, the corner post being connected to one leg of the Z bar and also to the web of the Z bar and the end plate being 40 connected to the other leg of the Z bar and to the corner post. 45

29. A box car having an angle corner post one leg of which covers the end of the end sheet and the other leg the side of the side sheet, a side plate having a horizontal flange or web and a vertical flange, the said vertical flange fastened by a gusset plate to the leg of the angle that embraces the side sheet and the horizontal flange or web of the side plate secured to the other leg of the angle post through the medium of an angle plate. 50

Signed in Chicago, in the State of Illinois, and county of Cook, this 18th day of 60 November, 1914.

WILLIAM ERASTUS WILLIAMS.
